UNITED STATES PATENT OFFICE.

SAMUEL W. HORST, OF LEMOYNE, PENNSYLVANIA.

COMBINED WEATHER-STRIP AND SASH-LOCK.

1,043,106.

Specification of Letters Patent.

Patented Nov. 5, 1912.

Application filed February 28, 1912. Serial No. 680,499.

To all whom it may concern:

Be it known that I, SAMUEL W. HORST, a citizen of the United States, residing at Lemoyne, in the county of Cumberland and State of Pennsylvania, have invented a new and useful Combined Weather-Strip and Sash-Lock, of which the following is a specification.

The present invention relates to improvements in a combined weather strip and sash lock for window sashes, and the primary object of the present invention is the provision of a novel form of weather strip disposed to be carried by the meeting rails of the two sashes of a window and co-act to interlock when the sashes are in closed position to provide a dust tight joint at such connection, the said co-acting devices being further provided with means disposed to be engaged by a lock carried by one or the other of the window sashes to wedge the co-acting members into locking position and thus more securely fasten the sashes together and tighten the joints between such co-acting members to prevent the admission of dust or air when the sashes are closed.

A further object of the present invention is the provision of a weather strip for the meeting rails of window sashes, constituting a strip of sheet metal disposed upon the adjacent faces of each of the meeting rails of the sash, one being provided with an upper flange while the other is provided with a lower flange, said strip and flanges being the full width of the window sashes, so that when the meeting rails of the sashes are in aligned position such metal strips will co-act or interlock to provide a dust and air proof joint at the meeting rails the full width of the window.

A still further object of the present invention is a novel form of locking means used in connection with the two weather strips carried by the meeting rails of two sashes to wedge the two weather strips into close and tight relation to insure a tighter joint at such points and at the same time lock the sashes in such closed position.

With the foregoing and other objects in view which will appear as the description proceeds, the invention resides in the combination and arrangement of parts and in the details of description hereinafter described and claimed, it being understood that changes in the precise embodiment of the

invention herein disclosed can be made within the scope of what is claimed without departing from the spirit of the invention.

In the drawings—Figure 1 is a vertical central sectional view through a window frame with two sashes disposed therein in closed position, the combined weather strip and sash lock being shown in operable relation thereto. Fig. 2 is a cross section through the upper sash and upper portion 60 of the window frame looking downwardly upon the meeting rails of the two sashes and showing the present invention in operable relation thereof. Fig. 3 is a perspective view of the adjacent portions of the upper 65 rail of the lower sash showing the cam lock engaging the weather strip. Fig. 4 is an enlarged detail sectional view of the two meeting rails of the sashes of the weather strip and sash lock in locked position. Fig. 70 5 is a perspective view of one of the weather strips *per se*.

Referring to the drawings, the numeral 1 designates the window frame which has disposed therein as is usual the lower sash 2 80 and the upper sash 3, said sashes being provided with the vertical and horizontal window guides and weather strips S and S' as clearly shown in Fig. 2.

The outer face of the upper meeting rail 4 85 of the lower sash 2 as clearly shown in Fig. 4 is provided with the grooved portion 5 in its lower corner and has disposed upon the outer face thereof, the metal weather strip or plate 6 which is of the full width of the 90 window sash and is so fitted as to have its upper flanged end 7 disposed above the meeting rail 4 and toward the meeting rail 12 of the upper sash. An aperture or slot 8 is formed in the body of the weather strip 6 95 above and in line with the upper face of the meeting rail 4 of the sash 2 while the flange 7 is provided with the peculiarly shaped receptacle as at 9 the purpose of which will later appear. The lower edge 10 of the 100 weather strip 6 is inturned as shown in Fig. 4 and terminates slightly below the recessed portion 5 and above the lower face of the meeting rail 12 of the sash 3. Mounted upon the adjacent face of the lower meeting rail 105 12 of the sash 3, and the rail 4 that carries the weather strip, is the metal weather strip 13 whose hooked flange 14, which is constructed similar to the flange 7 of the strip 6, is disposed in opposite direction so that the 110

hooked terminal 15 thereof when the sashes are in the position as shown in Fig. 4 will fit within the recess 5 of the meeting rail 4 and form a receptacle for the inturned ends 5 of the plate 6. The upper end 16 of the plate or weather strip 13 is projected above the upper face of the meeting rail 12 of the sash 3 and fits within the flange 8. By this means it will be seen that the raising and 10 lowering of the respective sashes or the moving of the respective meeting rails 4 and 12 toward and from each other, will bring the respective strips 6 and 13 into and out of interlocking position, and as the flanged portions 7 and 14 are so disposed as to receive the respective ends 10 and 16, the abutting faces of the respective weather strips 6 and 13 will be held snugly together and thus provide a means whereby dust or air cannot 15 pass between the adjacent faces of the meeting rails of the two sashes, when the same are in interlocking position.

The portion of the weather strip 13 above the upper face of the meeting rails 12 is 20 provided with an elongated slot 17 which is of lesser width than the slot 8 of the strip 6, so that the upper edge thereof as at *a* will normally be below the upper edge of *b* of the slot 8. In order to more securely lock 25 the strips 6 and 13 in the position as shown in Fig. 4 and also act as a sash lock for the two sashes 2 and 3, the screw 18 is employed to pivot the cam plate 19 upon the upper face of the meeting rail 4 of the lower sash. 30

This cam plate is provided with an operating lug or handle 20 and with the cam segment 21, the same being so positioned as to enter the respective slots 8 and 17 to force the plates into closer and locked engagement. 35

By this means it will be seen that the two plates 6 and 13 are locked snugly together and that the cam plate 19 will provide a means whereby the sashes may be locked in such closed position.

40 45 What is claimed is:

1. A weather strip and sash fastener having two members disposed respectively upon the meeting edges of two sashes and the full width of the sashes, said members having 50 coacting interlocking portions, and means for forcibly engaging both members when in interlocking position to lock said members together.
2. A weather strip and sash fastener, having two members disposed respectively upon the meeting edges of two sashes the full width thereof, said members each having co-acting interlocking portions, and a cam

lock carried by one sash for engaging both members to move them into locked relation. 60

3. The combination with two sashes, of a weather strip and fastener therefor, having a strip connected to the meeting edges of each sash and having a portion projecting above the rail of the sash to which it is attached, each of said strips being provided with a flange, said strips co-acting when the sashes are closed to incase one another, and means for engaging both strips to clamp them together. 70

4. The combination with two sashes, of a weather strip and fastener therefor, having a strip connected to the meeting edges of each sash and having a portion projecting above the rail of the sash to which it is attached, each of said strips being provided with a flange, said strips co-acting when the sashes are closed to incase one another, and a cam lock carried by one sash for engaging both strips to clamp the strips together. 80

5. The combination with two sashes, of a weather strip and fastener therefor, having a strip connected to the meeting edges of each sash and having a portion projecting above the rail of the sash to which it is attached, each of said strips being provided with a flange, said strips co-acting when the sashes are closed to incase one another, both of said strips being provided with centrally disposed elongated slots disposed to register 90 when in co-acting relation, and means carried by one of the sashes and disposed to enter the slots to lock said strips in clamped relation. 85

6. The combination with two sashes, of a weather strip and fastener therefor, having a strip connected to the meeting edges of each sash and having a portion projecting above the rail of the sash to which it is attached, each of said strips being provided with a flange, said strips co-acting when the sashes are closed to incase one another, both of said strips being provided with centrally disposed elongated slots disposed to register 95 when in coacting relation, and a cam lock 105 carried by one of the sashes and disposed for movement into and out of said slots when in registration to lock the strips together.

In testimony that I claim the foregoing 110 as my own, I have hereto affixed my signature in the presence of two witnesses.

SAMUEL W. HORST.
